US0D1025519S

(12) **United States Design Patent** (10) **Patent No.:** **US D1,025,519 S**
(45) **Date of Patent:** **** Apr. 30, 2024**

(54) **VACUUM CLEANER**

- (71) Applicant: **GUANGDONG SHUNDE PRETCYCARE INTELLIGENT TECHNOLOGY CO., LTD.**, Foshan (CN)
- (72) Inventor: **Chenglong Yu**, Foshan (CN)
- (73) Assignee: **GUANGDONG SHUNDE PRETCYCARE INTELLIGENT TECHNOLOGY CO., LTD.**, Foshan (CN)

(**) Term: **15 Years**

(21) Appl. No.: **29/857,793**

(22) Filed: **Oct. 26, 2022**

(30) **Foreign Application Priority Data**

- Aug. 22, 2022 (CN) 202230550031.X
- (51) LOC (14) Cl. **15-05**

(57) **CLAIM**

The ornamental design for a vacuum cleaner, as shown and described.

DESCRIPTION

FIG. 1 is a front perspective view of a vacuum cleaner showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a back perspective view thereof.

The broken lines in FIG. 7 depict portion of the vacuum cleaner, that form no part of the claimed design.

1 Claim, 7 Drawing Sheets
